TOY FIGURE

Hans Gustav Ehrenreich, Stilling, Denmark 8363
Filed June 13, 1972, Ser. No. 262,252

Claims priority, application Denmark Mar. 13, 1972

Term of patent 14 years

Int. Cl. D21—01
U.S. Cl. D34—15 AD

FIG. 1 is a perspective view of the toy figure according to the new design, in a position in which the nose is directed in a direction approximately halfway between straight forward and straight sideways;

FIG. 2 shows the toy figure of FIG. 1 with the nose in a direction straight forward;

FIG. 3 shows the toy figure of FIG. 2, but standing in a direction turned by 90° with regard to the position of FIG. 2;

FIG. 4 shows the toy figure of FIG. 2 turned around by 180°;

FIG. 5 is a top view of FIG. 3; and

FIG. 5a is a section taken along the line 5A—5A of FIG. 2.

I claim:

The ornamental design for the toy figure, as shown and described.
